UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

BURNER FLUE.

Application filed February 26, 1921. Serial No. 448,111.

To all whom it may concern:

Be it known that I, LEE S. CHADWICK, a citizen of the United States, residing at Shaker Heights Village, in the county of Cuyahoga and State of Ohio, have invented a certain new and useful Improvement in Burner Flues, of which the following is a full, clear, and exact description, reference being had to the accompanying drawings.

10 This invention relates to improvements in burners of the type wherein a drum or flue is supported above and in operative relation to the combustion device. In prevailing burners of this type there is a considerable waste of heat and an undue heating of the drum, especially in the region of its upper end.

15 The purpose of this invention is to correct these difficulties and increase the efficiency of the burner by conserving the heat formerly wasted and deflecting it by an auxiliary current of air away from the drum, the auxiliary air thus itself becoming heated and accordingly increasing the volume of hot air discharged from the flue.

These, with other and more specific objects, are attained in the embodiments of the invention illustrated in the drawings accompanying and forming a part hereof and wherein Fig. 1 is a central vertical section through a burner constructed in accordance with my invention; Fig. 2 is a section on the line 2—2 of Fig. 1, looking in the direction of the arrows; and Figs. 3 and 4 are views, similar to Fig. 1, of modified forms of the invention.

The combustion device or burner proper is designated, generally, by 1 and it is of the well-known type wherein a cylindrical wick 2 is guided between inner and outer wick tubes 3 and 4, respectively, and is adapted to be raised and lowered through the medium of a wick-raising spindle 5. A flame spreader 6 is supported by the combustion device in operative relation to the upper end of the wick. The space between the inner and outer wick tubes is supplied with liquid fuel from the pipe 10 wherewith it has communicative connection through the fitting 11 that is bound to the pipe by the clamp 12. The foregoing structure, being a common one, is so well known that a more detailed description thereof is deemed unnecessary.

Resting upon a ledge 15, which extends about the outer wick tube and is spaced a suitable distance from its upper end, are brackets 16 of a collar 17 that surrounds the upper portion of the combustion device and has its top edge spaced a comparatively short distance from the edge of the outer wick tube. A flange 18, provided with an upturned peripheral lip 19 and a staggered row of perforations 20, surrounds the collar 18 and has its inner edge secured thereto. A baffle 23, in the form of a flat ring, is supported by legs 24 from the flange 18 a suitable distance thereabove.

The lower end of a drum 30 is designed to rest upon the flange 19 immediately inside the upturned lip 19, and the upper end of the drum is directed inwardly as indicated at 31. The drum 30 is provided with an inner wall or shell 33 which, in the present form of the invention, extends from the upper end of the drum to a point slightly below its vertical center where it is flanged outwardly at 34 into contact with the drum, the upper end of the shell being shown as converging at substantially the same angle 80 as the portion 31 of the drum. A series of perforations 36 extend about the drum a short distance above the upper end of the shell 33. The upper portion of the shell is maintained at a given distance from the drum 30 by spacers 37, and in the present instance, the shell is supported by a bolt 38 which, with a shorter bolt 39, serve to attach a handle 40 to the drum. A window, designated 42 occupies the lower front portion of the drum, and it is surrounded by a frame 43 which holds a sheet of transparent material, such as isinglass, over the opening of the window.

When the burner is in operation, air is drawn in through the perforations 20 of the flange 18, a part being deflected about each edge of the baffle 23. As the air rises within the drum it commingles with the products of combustion and becomes heated, the intensity of the heat increasing as it advances toward the upper end of the drum. This of course results in the shell 33 acquiring a high degree of temperature and the heat that radiates from it is picked up by a current of air admitted through the perforations 36 and which flows upward through the space between the drum and

shell. This auxiliary air, besides serving to prevent overheating of the upper end of the drum 30, joins the main volume of heated air that rises through the drum and thereby contributes to the high efficiency of the burner.

Thus it will be seen that the arrangement above described not only increases the effectiveness of the burner by the conservation of heat that was formerly wasted, but the volume of heat expelled from the burner is enlarged; and furthermore the drum is maintained at a lower and more uniform temperature from top to bottom than is the case in burners equipped with the ordinary single wall drum. Mention might be made of the fact that the air which is directed about the outer edge of the deflector 23 sweeps up along the lower wall of the drum and prevents it from becoming as hot as it otherwise would.

In the form of the invention illustrated in Fig. 3, the shell 33^a extends to within a short distance of the lower end of the drum 30^a, and the row of perforations 36^a is accordingly situated in the region of the lower end of the drum. In this modification, the auxiliary current of air which passes through the space between the drum and shell 33^a may become more highly heated than in the former construction, but the present arrangement may not have the effect of keeping the upper end of the drum 30^a as cool as in the former case.

In Fig. 4 the inner wall 33^b is shown as extending below the lower end of the drum 30^b and resting upon the flange 18. In this form of the invention, the perforations in the drum are dispensed with and the auxiliary current of air is admitted directly into the space between the drum and shell.

An important feature of my present invention resides in the shape of the collar 17 and its relation to the top of the burner tubes 45 and to the elements 18 and 23 that are associated with and connected to it.

It will be observed that the upper edge of the collar 17 is spaced a comparatively short distance from and is in substantially the plane of the corresponding edge of the outer wick tube 4, in contradistinction to the types of collars heretofore employed in connection with burners of the class to which this invention relates, an example of which may be found in my prior United States Letters Patent No. 1,138,729, issued May 11, 1915, and wherein the upper end of the collar is flared outwardly and upwardly and extends quite a material distance above the plane of the top edge of the outer wick tube. As is well understood, the method of lighting these burners is by lifting or tilting the flue or drum sufficiently to afford access to the wick to which a lighted taper or match is applied, and with the former design of col-

lar, this operation was rendered quite difficult because of the fact that the exposed portion of the wick was completely surrounded by and was somewhat below the upper flared portion of the collar, making it 70 not only unhandy to apply the match or taper to the wick, but the comparatively low temperature of the metal whereof the collar was made tended to extinguish the flame of the match or taper. It was essential, however, in the former construction, to flare the upper end of the collar as described, for without this feature, and in the absence of some element which would perform its function, there was caused by the draft created 80 when the burner was in operation a humming sound of high pitch which was particularly annoying. The removal of the upper flared end of the collar, therefore, presented the problem of how to avoid that so-called 85 "musical flame", and this was answered by the inclusion of the present collar of the deflector 23 that is applied to the flange 18.

My present construction, therefore, possesses the advantage of being easy to light, 90 and is quiet of operation,

Having thus described my invention, what I claim is:

1. In combination with a burner of the character set forth, a collar supported by the 95 burner, a perforated flange surrounding the collar, and a double wall drum supported in operative relation to the flange and outside the zone of perforations whereby a quantity of fresh air is admitted to the drum 100 between the inner wall thereof and the flame, said drum having an opening for admitting air to the space between its walls.

2. In combination with a burner of the character set forth, a collar supported by the 105 burner, a perforated flange surrounding the collar, a double wall drum supported in operative relation to the flange and outside the zone of perforations whereby a quantity of fresh air is admitted to the drum between 110 the inner wall thereof and the flame, said drum having an opening for admitting air to the space between its walls, and a deflector spaced upwardly from the flange for directing a part of said air toward the drum 115 and a part toward the flame.

3. In combination with a burner of the character set forth, a collar supported by the 120 burner, a perforated flange surrounding the collar, a drum supported in operative 125 relation to the flange and outside the zone of perforations, a shell spaced inward from the wall of the drum and extending substantially to the upper end thereof, there being perforations opening through the drum into the space between the drum and shell, and a deflector spaced a comparatively short distance above the flange, the inner and outer edges whereof are spaced respectively from the collar and drum.

4. In combination with a burner of the character set forth, a collar supported by the burner, a perforated flange surrounding the collar, a drum supported by the flange outside the zone of perforations, a shell spaced inward from the wall of the drum and extending substantially to the upper end thereof, the lower end of the shell being turned outwardly into contact with the drum, there being air admitting openings in the drum that communicate with the space between the drum and shell, and a deflector spaced a comparatively short distance above the flange. 70
5. In combination with a burner of the character set forth, a collar supported by the burner, a perforated flange surrounding the collar, a drum supported by the flange outside the zone of perforations, a shell spaced inward from the wall of the drum and extending substantially to the upper end thereof, the lower end of the shell being turned outwardly into contact with the drum, there being air admitting openings in the drum that communicate with the space between the drum and shell. 80
6. A drum for use with burners of the character set forth, said drum comprising an inner and an outer wall that are spaced from each other, the inner wall extending approximately to the top of the outer wall and having its lower end turned outwardly into contact with the outer wall, and the outer wall having air admitting openings communicating with the space between the walls. 90
7. A drum for use with burners of the character set forth, said drum comprising an inner and an outer wall, means for maintaining the inner wall in radially spaced relation to the outer wall, a handle, and means connecting the handle to the drum and serving to hold the inner and outer walls together. 100
8. In a burner of the character set forth, in combination with the outer wick tube, a collar surrounding said wick tube and having its upper edge spaced from and in substantially the plane of the corresponding edge of the tube, and a deflector surrounding the collar in spaced relation thereto. 110
9. In a burner of the character set forth, in combination with the outer wick tube, a collar surrounding said wick tube and having its upper edge spaced a comparatively short distance from and in substantially the plane of the corresponding edge of said wick tube, and a deflector surrounding the collar and supported therefrom and having an inner edge that is spaced a comparatively short distance from and below the upper edge of the collar. 120
10. In a burner of the character described, in combination with the outer wick tube, of an upwardly converging collar surrounding the wick tube and having its upper
- edge spaced a comparatively slight distance from and in substantially the plane of the corresponding edge of the wick tube, a perforated flange surrounding the collar, and a deflector supported by and spaced above said flange. 130
11. In combination with a burner of the character set forth, a collar supported by the burner, a perforated flange surrounding the collar, and a double wall drum resting directly upon the flange outside the zone of perforations so that fresh air admitted through said perforations may rise between the inner wall of the drum and the flame, said drum having an opening for admitting air to the space between its walls. 75
12. A drum for use with burners of the character set forth, said drum comprising an outer wall having an annular converging top, an inner wall spaced from the outer wall and having a converging upper end supported in spaced relation to the annular top of the outer wall, the lower end of the inner wall being directed outwardly into engagement with the outer wall, the outer wall 85 having air admitting openings above the lower end of the inner wall. 90
13. A drum for use with burners of the character set forth, said drum comprising a cylindrical shell having an annular converging top wall, an inner wall spaced from the shell and having a converging top in spaced relation to the annular wall of the shell, the lower end of the inner wall being flanged outwardly to meet the shell at about 100 its vertical center, the shell having air admitting openings above the lower end of the inner wall. 95
14. In combination with a burner of the character set forth, a collar supported by the burner, a perforated flange surrounding the collar, and a double wall drum supported in operative relation to the flange outside the zone of perforations whereby a quantity of fresh air is admitted to the drum between the wall thereof and the flame, said drum having openings for the circulation of air through the space between its walls. 110
15. In combination with a burner of the character set forth, a collar supported by the burner, a perforated flange surrounding the collar, a double wall drum supported in operative relation to the flange outside the zone of perforations whereby a quantity of fresh air is admitted to the drum between the wall thereof and the flame, said drum having openings for the circulation of air through the space between its walls, and a deflector spaced upwardly from the flange for directing fresh air toward the wall of the drum. 125
16. In combination with a burner of the character set forth, a double wall drum supported in operative relation to the burner and in such manner that a quantity of fresh

air is admitted to the drum between the wall thereof and the flame, the drum having openings for the circulation of air through the space between its walls.

5 17. In combination with a burner of the character set forth, a double wall drum supported in operative relation to the burner

in such manner that a quantity of fresh air is admitted to the drum between the wall of the drum and the flame.

10 In testimony whereof, I hereunto affix my signature.

LEE S. CHADWICK.
